Primary Examiner — Rhea Shields(57) **CLAIM**

The ornamental design for an electrical plug, as shown and described.

DESCRIPTION

FIG. 1 is a top perspective view showing my new design; FIG. 2 is a top view thereof; FIG. 3 is a left elevation side view thereof; FIG. 4 is a right elevation side view thereof; FIG. 5 is a top perspective view showing a second embodiment of my new design; FIG. 6 is a top view of the second embodiment; FIG. 7 is a left side view of the second embodiment; FIG. 8 is a right side view of the second embodiment; FIG. 9 is a top perspective view showing a third embodiment of my new design; FIG. 10 is a top view of the third embodiment; FIG. 11 is a left side view of the third embodiment; FIG. 12 is a right side view of the third embodiment; and, FIG. 13 is a cross-sectional view of the third embodiment taken along section lines 13-13 in FIG. 9.

In the drawings, the broken lines are for the purpose of illustrating environment only and form no part of the claimed design.

1 Claim, 3 Drawing Sheets(56)
